UNITED STATES PATENT OFFICE.

JOHN W. CASTLE, OF LEOMINSTER, MASSACHUSETTS.

DESIGN FOR A STRAND-SUPPORTING CARD FOR FUMIGATORS.

SPECIFICATION forming part of Design No. 34,057, dated February 12, 1901.

Application filed January 10, 1901. Serial No. 42,809. Term of patent 3½ years.

To all whom it may concern:

Be it known that I, JOHN W. CASTLE, a citizen of the United States, residing at Leominster, in the county of Worcester and State of Massachusetts, have invented and produced a new and original Design for Strand-Supporting Cards for Fumigators, of which the following is a specification, reference being had to the accompanying drawings, forming part thereof.

Figure 1 is a plan view of a strand-supporting card for fumigators, showing my new design. Fig. 2 is a sectional view taken on line 2, Fig. 1. Fig. 3 is a sectional view taken on line 3, Fig. 1.

As shown in the drawings, the leading or material feature of my design consists of the oblong flat figure having the central parallel side edges *a* and the opposite enlarged curved ends *c d*, one of said ends being provided with

the round hole *e* near the edge and the opposite end being centrally provided with the longitudinally-cut V-shaped slit *g*. The edges of the card are turned under and inward into the narrow folds *h*. The slit *g* and hole *e* are so located that a longitudinal line running centrally through the card would intersect them. 25

Having described my invention, what I claim as new, and desire to secure by Letters Patent, is—

The design for a strand-supporting card for fumigators, as herein shown and described.

In testimony whereof I have signed my name to this specification in the presence of 35 two subscribing witnesses.

JOHN W. CASTLE.
